ELECTRIC SWITCH

Arthur Palme and Orin P. McCarty, Pittsfield,
Mass., assignors to General Electric Company,
a corporation of New York

Application December 4, 1945, Serial No. 632,735

8 Claims. (Cl. 200—146)

1

Our invention relates to electric switches and more particularly to electric switches having sequential contacts which are capable of interrupting moderate power currents such as transformer magnetizing currents or the like, as well as for carrying normal load currents and also functioning to disconnect the circuit. Specifically, our invention is an improvement on concurrently filed copending Warnock application, Serial No. 632,734, assigned to the same assignee as the present application.

Such electric switches for interrupting the magnetizing current of power transformers may be immersed in a liquid insulating dielectric such as oil or a halogenated hydrocarbon. When arcs are drawn in oil there is always the hazard of fire. On the other hand, when arcs are drawn in a non-inflammable dielectric, there is always the possibility of some decomposition of the halogenated hydrocarbons and the consequent formation of corrosive decomposition products.

It is well known that when power transformers are connected to a power source, a fairly high so-called transformer inrush current results. A circuit interrupter which is capable of interrupting transformer magnetizing currents may not be capable of carrying the transformer inrush currents even for a short period of time. It would be desirable to provide a switch of the above mentioned type in which the interrupting contacts were not required to carry the transformer inrush currents.

Accordingly, it is an object of our invention to provide a new and improved sequential circuit controlling electric switch having circuit closing contacts that are capable of carrying fairly high currents and are sequentially interrelated with hermetically sealed interrupting or arcing contacts that are capable of efficiently interrupting moderate load currents in high voltage power circuits in disconnecting such power circuits.

It is another object of our invention to provide a switch of the above described type capable of being immersed in any form of liquid insulating dielectric without danger of fire or deleterious effect on the liquid dielectric when operating to interrupt moderate load currents.

Still another object of our invention is to provide a switch for interrupting the magnetizing current of power transformers which switch includes sequentially operable circuit closing contacts and interrupting contacts arranged so that the interrupting contacts are never subjected to transformer inrush currents.

Further objects and advantages of our inven-

tion will become apparent as the following description proceeds and the features of novelty which characterize our invention will be pointed out with particularity in the claims annexed to and forming a part of this specification.

For a better understanding of our invention reference may be had to the accompanying drawing in which Fig. 1 is an elevational view, partly in section, of a switch embodying our invention associated with a device such as a power transformer, and Fig. 2 is an enlarged view of a portion of Fig. 1.

Referring now to the drawing, we have illustrated an electric switch generally indicated at 1, which is shown as a transformer disconnecting switch. A portion of the transformer is generally illustrated at 2 and includes a housing 3 which supports an insulating bushing 4 through which electrical connections from the transformer are brought out to a circuit terminal 5. Switch 1 is mounted within a container 6 supported from transformer housing 3 and preferably both the transformer housing 3 and the container 6 are filled with a liquid insulating dielectric which may comprise oil or a halogenated hydrocarbon. It should be understood that, although we have disclosed our switch as arranged to be immersed in a liquid insulating dielectric, it is equally capable of satisfactory operation when mounted in air in the manner disclosed in the above mentioned copending Warnock application.

A second circuit terminal 7 is illustrated in Fig. 1 as being supported on an insulating bushing 8 fastened within container or housing 6 and electrical connections from terminal 7 extend through bushing 8 to any suitable power circuit such as a power line or the like.

Circuit terminals 5 and 7 are arranged to be electrically interconnected by a pair of relatively movable main current carrying switch members illustrated as a stationary switch member or contact comprising contact bars 9 provided with contact clips 10, and a movable blade or contact 11 pivotally mounted as indicated at 12, to suitable means within housing 6. The numeral 10 will hereinafter be used when referring generally to the stationary main current carrying contact. Movable blade 11 is provided with a contact ring 13 which is engaged in sliding electrical engagement with contact fingers or brushes 14 supported from terminal 7.

For the purpose of interrupting moderate power currents when the electric switch of our invention is to be opened, there is provided a circuit interrupter generally indicated at 15

which is carried by one of the relatively movable switch members. As illustrated in the drawing, circuit interrupter 15 is associated with movable blade 11. It should be understood, however, that circuit interrupter 15 could be associated with the stationary contact 10.

Circuit interrupter 15 comprises a hermetically sealed enclosure 16 formed of insulating material, such as glass or the like, which is essentially an evacuated envelope for housing a pair of relatively movable arcing or interrupting contacts 17 and 18. Interrupting contact 17 is illustrated as a stationary contact and is electrically connected to movable blade 11 by means of a flexible conductor 19. Movable arcing contact 18, on the other hand, is mounted on a rod 20 which extends outside of housing 16 through a flexible thin-walled metallic diaphragm 21. The portion of rod 20 extending outside of housing 16 is, in effect, a contact actuating member and is provided with the end portion 22 which will hereinafter be referred to as actuating member 22. As illustrated in the drawing, relatively movable arcing or interrupting contacts 17 and 18 are preferably biased to the closed position by means of the flexible metallic diaphragm 21 and are opened by operation of actuating member 22 causing flexing of diaphragm 21. Essentially the circuit interrupter 15 is a vacuum switch of the type disclosed in Jones Patent 2,383,973, granted September 4, 1945, and assigned to the same assignee as the present application.

Circuit interrupter 15 is illustrated as being supported on a block of insulating material 23 by means of a band 24 partially encircling a portion of the housing thereof. Insulating material 23 is supported by suitable means on moving blade 11.

Also supported on insulating block 23 is a double armed lever 25 comprising an auxiliary terminal 26 and a switch actuating arm 27. Double armed lever 25 is pivotally mounted to insulating block 23 as indicated at 28 in such a position that clockwise rotation as viewed in Fig. 2 will cause arm 27 to engage contact actuating member 22 with the resultant opening of arcing or interrupting contacts 17 and 18. A suitable spring 29 tends to hold double armed lever 25 normally in the midposition shown in Fig. 2 with a small gap between arm 27 and contact actuating member 22, thereby permitting slight movement of double armed lever 25 without opening of the arcing contacts 17 and 18. The double armed lever 25, which is formed of conducting material and furnishes an auxiliary terminal 26, is electrically connected by means of a flexible electrical conductor 30 with rod 20 and consequently with movable arcing contact 18.

Associated with the stationary contact 10 adapted to engage movable blade 11 is a supporting member 31 formed of insulating material which extends for a considerable distance along the path of movable blade 11 during the circuit opening operation. Insulating supporting member 31 is provided along a portion of its under surface with a conducting liner 32 electrically connected to one of the contact clips 10. Conducting liner 32 is, in effect, an auxiliary contact surface in the form of a cam surface. At a distance X from the end of the cam surface or metal liner 32, not connected to stationary contact 10, is a downwardly extending surface or portion designated by the numeral 33 in Fig. 2. The auxiliary contact surface comprising the liner 32 during the circuit opening operation is adapted

to be engaged by the auxiliary terminal 26. It is obvious that when this occurs the auxiliary contact surface 32, auxiliary terminal 26, flexible lead 38, rod 20, arcing contacts 17 and 18 and flexible lead 19 provide a shunt electrical connection across the relatively movable switch members 10 and 11. An important feature of our invention is the arrangement of the current carrying contacts and the arcing contacts whereby the current carrying contacts are first opened, thereby shunting all of the power current through circuit interrupter 15. In the fully closed position of the switch shown by solid lines in Figs. 1 and 2, all of the current flows through the current carrying contacts and the shunt circuit is open by virtue of the fact that auxiliary contact surface 32 and auxiliary terminal 26 are electrically disengaged.

During the circuit opening operation contact blade 11 rotates about pivot 12 in a counterclockwise direction, as viewed in Fig. 1. However, before disengagement between current carrying contacts occurs, auxiliary terminal 26 electrically engages cam surface 32 thereby completing the shunt circuit through interrupting contacts 17 and 18. Continued opening movement of switch 1 causes the main current carrying contacts to be completely disengaged with the resultant transfer of all the current to the shunt circuit comprising arcing contacts 17 and 18. After the current carrying contacts have been completely disengaged and the current transferred to the shunt circuit, the auxiliary terminal 26 of double armed lever 25 engages the portion 33 of cam surface 32 causing lever 25 to rotate in a clockwise direction with the resultant engagement of arm 27 of actuating member 22 and the opening of interrupting contacts 17 and 18. The arc drawn will be interrupted within the evacuated envelope in a very effective manner even though the voltage involved may be high. Continued movement of blade 11 for the distance X in Fig. 2 maintains electric contact between auxiliary terminal 26 and cam surface 32 to give ample time for actual current rupture. Continued movement of blade 11 for the distance Y prevents the spring 29 from returning the double armed lever 25 to its intermediate position whereby a double gap in the shunt circuit is provided, one between arcing contacts 17 and 18 and an additional gap between auxiliary terminal 26 and cam surface 32. When the switch reaches its fully open position shown in dotted lines in Fig. 1, double armed lever 25 has assumed its intermediate position and arcing contacts 17 and 18 have reclosed.

Although the interrupting contacts 17 and 18 are very effective to interrupt high voltage arcs, there is a possibility that they might be damaged by the heavy inrush currents which flow when the transformer is connected to a power supply. It is an important feature of our invention that during the switch closing operation double armed lever 25 first engages insulating member 31 to rotate it in a counterclockwise direction so that it cannot engage cam surface 32 and complete the shunt circuit through arcing contacts 17 and 18 until after the main current carrying contacts 10 and 11 have closed to take the inrush current. When the main current carrying contacts are fully closed, double armed lever 25 is free to move clockwise to its original position under the influence of spring 29 after the free end of the arm 25 rides off the inner end of the conducting liner 32 because the pivotal

point 28 is low enough to permit such movement.

In view of the detailed description included above, the operation of our invention will be obvious to those skilled in the art.

It will be understood that the insulating evacuated envelope 16 prevents any arc which is drawn from in any way deleteriously affecting the surrounding medium whether it be air, oil or other insulating liquid dielectric.

It is furthermore obvious that with our invention we have utilized the very favorable characteristic of vacuum switches of interrupting moderate currents at high voltages while not subjecting the vacuum switch to high transformer inrush currents.

While we have shown and described a particular embodiment of our invention, it will be obvious to those skilled in the art that various changes and modifications may be made without departing from our invention in its broader aspects and we, therefore, aim in the appended claims to cover all such changes and modifications as fall within the true spirit and scope of our invention.

What we claim as new and desire to secure by Letters Patent of the United States is:

1. In a switch, a pair of relatively movable cooperating contact members including a stationary contact and a movable blade, an insulating support on said blade, a vacuum switch mounted on said insulating support comprising a pair of interrupting contacts enclosed by an evacuated envelope having a flexible metallic diaphragm as a wall portion thereof, an actuating member extending through said diaphragm for operating said interrupting contacts from outside said envelope, a conducting cam surface associated with said stationary contact, a conducting member pivoted to said insulating support and electrically connected to said blade through said arcing contacts so as to complete a circuit in parallel with said contact members when said conducting member engages said cam surface, and means on said cam surface for causing movement of said conducting member to open said interrupting contacts and interrupt the current which has been transferred from said contact members to said interrupting contacts.

2. In a switch for interrupting transformer magnetizing currents of the type immersed in an insulating liquid dielectric, a pair of relatively movable cooperating contact members, a pair of relatively movable arcing contacts, an evacuated envelope for housing said arcing contacts and including a flexible metallic diaphragm whereby relative movement of said arcing contacts may be obtained by actuation of the diaphragm exteriorly of the envelope, means for normally biasing said arcing contacts to the closed position, said evacuated envelope being supported on one of said contact members but insulated therefrom, a pivotally mounted lever electrically connected to one of said contact members through said arcing contacts, and means electrically connected with said other contact member for electrically engaging said lever to contact said arcing contacts in shunt with said contact members following initial movement of said contact members and before the members have moved out of electrical engagement, said last mentioned means being arranged to cause pivotal movement of said lever to open said arcing contacts and interrupt the circuit in said evacuated envelope following electrical disengagement of said contact members.

3. In a switch, a pair of relatively movable cooperating contact members, a pair of relatively movable arcing contacts, an evacuated envelope for housing said arcing contacts and including a flexible diaphragm whereby relative movement of said arcing contacts may be obtained by actuation of the diaphragm exteriorly of the envelope, said evacuated envelope being supported by one of said contact members, and means including a conducting cam surface electrically connected to said other contact member for connecting said arcing contacts in shunt with said contact members following initial movement of said contact members and before the members have moved out of electrical engagement, and means cooperating with said cam surface to cause opening of said arcing contacts to interrupt the circuit in said evacuated envelope following electrical disengagement of said contact members.

4. In a switch of the type adapted to be immersed in an insulating liquid dielectric, a pair of relatively movable cooperating contact members, a pair of relatively movable arcing contacts, an evacuated envelope for housing said arcing contacts and including a flexible diaphragm whereby relative movement of said arcing contacts may be obtained by actuation of the diaphragm exteriorly of the envelope, means for normally biasing said arcing contacts to the closed position, said evacuated envelope being supported by one of said contact members, a conducting lever movable to actuate said diaphragm externally of said envelope to open said arcing contacts, said lever being electrically connected to said one contact member through said arcing contacts, and means associated with said other contact member for engaging said lever following initial movement of said contact members and before the members have moved out of electrical engagement to connect said arcing contacts in shunt with said contact members, said last mentioned means being arranged to move said lever to open said arcing contacts to interrupt the circuit in said evacuated envelope following electrical disengagement of said contact members, whereby said envelope encloses the arc drawn and prevents it from adversely affecting said liquid dielectric.

5. In a switch, a pair of relatively movable cooperating contact members including a stationary contact and a movable blade, an insulating support on said blade, a vacuum switch mounted on said insulating support comprising a pair of normally closed interrupting contacts enclosed by an evacuated envelope having a flexible diaphragm as a wall portion thereof, an actuating member extending through said diaphragm for operating said interrupting contacts from outside said envelope, a conducting cam surface associated with said stationary contact, a conducting member pivoted to said insulating support and electrically connected to said blade through said arcing contacts so as to complete a circuit in parallel with said contacts when said conducting member engages said cam surface, and means on said cam surface for causing movement of said conducting member to open said interrupting contacts and interrupt the current which has been transferred from said contact members to said interrupting contacts.

6. In a switch, a pair of relatively movable cooperating contact members including a stationary contact and a movable blade, an insulating support on said blade, a vacuum switch mounted on said insulating support comprising

a pair of normally closed interrupting contacts enclosed by an evacuated envelope having a flexible diaphragm as a wall portion thereof, an actuating member extending through said diaphragm for operating said interrupting contacts from outside said envelope, a conducting cam surface associated with said stationary contact, a conducting lever pivoted to said insulating support and electrically connected to said blade through said arcing contacts so as to complete a circuit in parallel with said contacts when said lever engages said cam surface, and means on said cam surface for causing movement of said lever to engage said actuating member thereby opening said interrupting contacts to interrupt the current which has been transferred from said contact members to said interrupting contacts.

7. In a switch, a pair of relatively movable cooperating contact members including a stationary contact and a movable blade, an insulating support on said blade, a vacuum switch mounted on said insulating support comprising a pair of normally closed interrupting contacts enclosed by an evacuated envelope having a flexible diaphragm as a wall portion thereof, an actuating member extending through said diaphragm for operating said interrupting contacts from outside said envelope, a conducting cam surface having a depressed portion electrically connected to said stationary contact, a conducting lever pivoted to said insulating support and electrically connected to said blade through said arcing contacts so as to complete a circuit in parallel with said contacts when said lever engages said cam surface prior to disengagement of said contacts said depressed portion of said cam surface causing movement of said lever to open said interrupting contacts subsequent to electrical disengagement of said contact members.

8. In a switch, a pair of relatively movable cooperating contact members including a stationary contact and a movable blade, in insulating support on said blade, a vacuum switch

5 fixedly mounted on said insulating support comprising a pair of normally closed interrupting contacts enclosed by an evacuated envelope having a flexible diaphragm as a wall portion thereof, an actuating member extending through said diaphragm for operating said interrupting contacts from outside said envelope, a conducting cam surface associated with said stationary contact, a lever pivoted to said insulating support and electrically connected to said blade through said arcing contacts so as to complete a circuit in parallel with said contacts when said conducting member engages said cam surface, said lever being positioned so that when rotated it engages said actuating member to open said interrupting contacts, means normally positioning said lever out of engagement with said actuating member, and means on said cam surface for causing movement of said lever to open said interrupting contacts and interrupt the current which has been transferred from said contact members to said interrupting contacts.
